[57] CLAIM

The ornamental design for a floor mat for placement at front of toilet, substantially as shown and described.

DESCRIPTION

FIG. 1 is a partial front, top and left side perspective view of a floor mat for placement at front of toilet showing my new design in which the rear wall of said floor mat is vertical and plain;

FIG. 2 is an enlarged top plan view;

FIG. 3 is a bottom plan view thereof;

FIG. 4 is a front elevational view thereof; and

FIG. 5 is a more enlarged sectional view taken along line "5—5" of FIG. 2.

FIG. 1

FIG. 5

FIG. 2

FIG. 3

FIG. 4
